[57] CLAIM

The ornamental design for a hat carrier, as shown and described.

DESCRIPTION

FIG. 1 is a bottom perspective view of a hat carrier showing my new design;

FIG. 2 is a top plan view thereof;

FIG. 3 is a bottom plan view thereof;

FIG. 4 is a side elevational view thereof, all sides being substantially identical except for the attached chain; and FIG. 5 is a top perspective view thereof, the lid being shown removed.
